UNITED STATES PATENT OFFICE.

ROBERT HALLOWELL RICHARDS, OF BOSTON, MASSACHUSETTS.

JIG.

1,230,433.

Specification of Letters Patent. Patented June 19, 1917.

Application filed March 31, 1916. Serial No. 88,033.

To all whom it may concern:

Be it known that I, ROBERT H. RICHARDS, a citizen of the United States, residing at Boston, in the county of Suffolk and State 5 of Massachusetts, have invented a certain new and useful Improvement in Jigs, of which the following is a specification.

My invention relates to jigs, and particularly to the discharge mechanism thereof. 10 While not limited in its utility to use with jigs of the pulsator type, it attains its fullest advantages when combined with such jigs and I illustrate it in this relation.

Briefly stated, the invention involves the 15 use of a pan or cup discharge for the concentrates, the pan or cup being rocked or oscillated toward and from the discharge orifice. Additional features of the invention involve the general arrangement of the jig 20 structure to permit the best use of this discharge.

A successful embodiment of the invention is illustrated in the accompanying drawings in which:—

25 Figure 1 is an elevation of the complete device looking at the discharge end;

Fig. 2 is a side elevation of the same;

Fig. 3 is a fragmentary perspective showing the discharge mechanism; and

30 Fig. 4 is a fragmentary vertical section through the hutch, screen and discharge chambers.

In the drawings, 6 represents the hutch casting, which is supported on the frames. 7. 35 Connected to the hutch casting 6 by means of lugs and taper keys 8 is the screen box 9 carrying a screen 10 of suitable mesh. Material to be treated in the jig is fed to a box 11 bolted to the screen box as shown and 40 discharging directly into the screen box at the screen level. The discharge from the screen is partly into and partly over a pocketed casting 12 bolted to the screen box 9, the tailing passing over the casting 12 and 45 out through a spout 13 formed thereon, and the concentrate flowing from the screen into a chamber or pocket 14.

The opening 15 leading from the screen box 9 to chamber 14 of casting 12 extends 50 the entire width of the screen. Where no lag bed is to be used the bottom of opening 14 is at the screen level, as shown, but where a lag bed is to be used the screen is set lower than the bottom of opening 14 so 55 that the bed will be retained, as is usual in this art. The opening 15 is adjusted by a

vertically adjustable plate 16 which serves to define the line of division between concentrate and tailing. A vent pipe 17 is provided to prevent the trapping of air in the chamber 14 and extends upward above the level of the tailing flowing out through spout 13.

The jiggling action is secured by a pulsator valve mechanism such as described and 65 claimed in my prior Patents No. 901,474, dated October 20, 1908, and No. 901,475, dated October 20, 1908. This mechanism need not therefore be described in detail here. It involves a rotary balanced valve 70 18 placed just beyond an air chamber 19 in a supply pipe 20 through which water reaches the valve under suitable head. The valve 18 is rotated at proper speed by a belt (not shown) running on the wheel 21 and 75 delivers water in successive unidirectional pulses near the bottom of hutch 6. The air chamber 19 relieves water hammer in the supply pipe 20 and intensifies the pulsing action. An air vent valve 22 permits the 80 release of air from chamber 19 to adjust the length of the air column. A stop valve 23 controls the rate of water flow.

While as above stated the pulsing water enters the hutch 6 near the bottom thereof, 85 there is a pocket 24 at the extreme bottom to catch the hutch concentrate which passes through the screen and downward through the pulsing water. From here it is drawn off through the opening 25.

The concentrate which enters the chamber or pocket 14 is constantly drawn off through a pipe discharge 26 which extends downward therefrom. The pipe 26 dips into a pan 27 having an overflow barrier 28 at one 95 end over which barrier the concentrate discharges. The pan 27 is pinned at one end to the links 29 which at their other ends are pinned to the yoke 30. The yoke 30 is carried on a rod 31 which is vertically adjustable in guides 32 on the casting 12 and is supported therein by a nut wheel 33 threaded on the end of rod 31 and bearing against the upper one of the guides 32. A wing nut 34 also threaded on rod 31 serves to clamp 100 wheel 33 in adjustment.

The end of pan 27 remote from links 29 is mounted on a crank 35 which is formed on the end of shaft 36. This shaft 36 turns in bearings 37 on the hutch casting 6 and 110 carries a belt wheel 38. The hub of pulley 21 is grooved at 39 and a belt 40 runs in

this groove and around wheel 38 so that shaft 36 is driven at a relatively slow rotative speed when the rotary valve is driven.

In the operation of the jig the rotary valve is driven at the proper speed and the stop valve 23 is opened to admit water at the proper rate. This causes the pulsing upward water flow through the screen, characteristic of this type of jig. Material to be treated is fed to the feed box 11 and flows from there across the screen 10. The lighter particles are carried to the top and the heavier settle to the screen, so that the lighter particles flow out over the overflow 13 and the heavier enter the chamber 14.

The heavier particles, which form the concentrate are discharged from chamber 14 through the pipe 26 to the pan 27. The oscillation of this pan toward and from the end of pipe 26 under the action of crank 35 keeps the pipe 26 from clogging and causes the particles of concentrate gradually to overflow barrier 28 to a suitable receptacle or launder (not shown). By turning hand wheel 33 the pan 27 may be adjusted to and from the end of pipe 26 to vary the rate of discharge of concentrate.

While the oscillation of the pan toward and from the end of pipe 26 is regarded as the movement most vitally important to the discharging action, it should be noted that the pan has a compound movement, due to its direct connection with the crank 35. The pan moves in an oval path with reference to the end of the pipe, so that it oscillates toward and from the end of the pipe and also transversely with reference thereto. This transverse movement produces a shifting of the discharged material in the pan which facilitates the discharge of succeeding portions of the concentrate.

The discharge arrangement above described gives freedom from clogging, and reduces the quantity of water flowing out with the concentrate. The rate of discharge is readily adjusted and all working parts are visible and accessible. In case it is desired to stop the discharge of concentrate this can be done at once and without destroying any adjustments, by merely drawing up rod 31 until the pan 27 closes pipe 26.

The discharge mechanism is not restricted in its utility to jigs in which the concentrate is taken off at the tail end of the jig as here illustrated nor to pulsator jigs, as its advantages may be realized in whole or in part when applied to other types of jig.

Having thus described my invention, what I claim is:—

60 1. The combination of a jig including the usual screen; a chamber for receiving the heavier materials flowing from said screen; a depending discharge tube leading from said chamber; a pan into which said tube dips, said pan having a barrier for retain-

ing a bed of discharging material around the depending end of said tube; and means for reciprocating said pan toward and from the end of said tube while the jig is in operation.

2. The combination of a jig including the usual screen; a chamber for receiving the heavier material flowing from said screen; a depending discharge tube leading from said chamber; a pan into which said tube dips, said pan having a barrier for retaining a bed of discharging material around the depending end of said tube; means for reciprocating said pan toward and from the end of said tube while the jig is in operation; and means for adjusting said pan toward and from the end of said tube for adjusting the rate of discharge.

3. The combination of a jig including the usual screen; a chamber for receiving the heavier materials flowing from said screen; a depending discharge tube leading from said chamber; a pan into which said tube dips; a swinging link supporting one end of said pan; means for adjusting said link to move said pan toward and from the end of said tube; a rotatable member having a crank pin journaled in the other end of said pan; and means for rotating said member.

4. The combination of a jig including the usual screen; a chamber for receiving the heavier materials flowing from said screen; a depending discharge tube leading from said chamber; a pan into which said tube dips, said pan having a barrier for retaining a bed of discharging material around the end of said tube; and means for oscillating said pan with a compound movement in an endless loop path toward and from the end of said tube and transversely with reference thereto while the jig is in operation.

5. The combination of a jig including the usual screen; a chamber for receiving the heavier materials flowing from said screen; a depending discharge tube leading from said chamber; a pan into which said tube dips; a swinging support for one end of said pan; a crank directly connected to the other end of said pan to support the same; and means for rotating said crank.

6. The combination of a stratifying separator; a chamber for receiving the heavier materials flowing from said separator; a depending discharge tube leading from said chamber; a pan into which said tube dips, said pan having a barrier for retaining a bed of discharging material around the depending end of said tube; and means for reciprocating said pan toward and from the end of said tube while the jig is in operation.

7. The combination of a stratifying separator; a chamber for receiving the heavier materials flowing from said separator; a depending discharge tube leading from said

chamber; a pan into which said tube dips, said pan having a barrier for retaining a bed of discharging material around the depending end of said tube; means for reciprocating said pan toward and from the end of said tube while the jig is in operation; and means for adjusting said pan toward and from the end of said tube for adjusting the rate of discharge.

10 8. The combination of a stratifying separator; a chamber for receiving the heavier materials flowing from said separator; a depending discharge tube leading from said chamber; a pan into which said tube dips; a swinging link supporting one end of said pan; means for adjusting said link to move said pan toward and from the end of said tube; a rotatable member having a crank pin journaled in the other end of said pan; and

20 means for rotating said member.

9. The combination of a stratifying separator; a chamber for receiving the heavier

materials flowing from said separator; a depending discharge tube leading from said chamber; a pan into which said tube dips, 25 said pan having a barrier for retaining a bed of discharging material around the end of said tube; and means for oscillating said pan with a compound movement in an endless loop path toward and from the end of 30 said tube and transversely with reference thereto while the jig is in operation.

10. The combination of a stratifying separator; a chamber for receiving the heavier materials flowing from said separator; a depending discharge tube leading from said chamber; a pan into which said tube dips; a swinging support for one end of said pan; a crank directly connected to the other end of 35 said pan to support the same; and means for 40 rotating said crank.

In testimony whereof I have signed my name to this specification.

ROBERT HOLLOWELL RICHARDS.
